UNITED STATES PATENT OFFICE

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed September 10, 1927, Serial No. 218,772. Renewed August 29, 1929.

My invention relates to railway traffic controlling apparatus, and particularly to apparatus of the type wherein traffic controlling current is periodically supplied to the track 5 rails.

One feature of my invention is the provision of means for periodically supplying current to the track rail without moving parts.

I will describe one form of apparatus embodying my invention, and will then point out the novel features thereof in claims.

The accompanying drawing is a diagrammatic view showing one form of apparatus embodying my invention.

15 Referring to the drawing, the reference characters 10 and 10^a designate the track rails of a railway along which traffic normally moves in the direction indicated by the arrow, and which rails are divided into sections by means of insulated joints 11. I have illustrated my invention as applied to the exit end of only one track section, but it is understood that in actual practice similar apparatus may be applied to each section over 20 an extended stretch of track.

The track rails 10 and 10^a are supplied with alternating train governing current from the secondary 2 of a transformer T, the primary 1 of which is constantly supplied with alternating current from a source not shown in the drawing. Interposed between the secondary 2 and one of the track rails is a first winding 5 of reactor A having an iron core 4 and a second winding 6. The transformer T is 30 provided with a second secondary 3 which is connected with the input terminals of a rectifier R, and the output terminals of the rectifier R are connected with the reactor winding 6 through a neon tube N. The circuit for the reactor winding 6 and neon tube N, which circuit I will term the control circuit for reactor A is provided with a plurality of multiple paths including condensers C^A, C^B, C^C, respectively. The branch path including condenser C^A also includes a resistance 8^a and a contact 9^a. The branch path including condensers C^B and C^C are similarly provided with resistances 8^b and 8^c, and contacts 9^b and 9^c. The condensers C^A, C^B and C^C have 40 different capacity values. The contacts 9^a, 9^b

and 9^c may be controlled in any suitable manner, such for example by traffic conditions in advance, the only essential characteristic being that any one or any group of these contacts may be closed. A variable resistance 7 is preferably included in the control circuit 55 between one of the output terminals of the rectifier R and the point of connection of the first condenser path with this circuit.

The operation of the apparatus is as follows: First assuming that contact 9^a is closed, as shown in the drawing, the condenser C^A will become gradually charged through the resistances 7 and 8^a until the voltage across the terminals of this condenser is great 60 enough to render the neon tube N conductive. When the neon tube becomes conductive, current will flow from the rectifier R through the control winding 6, and the condenser C^A will gradually discharge through this winding until the voltage across the condenser drops to such value that the neon tube again becomes non-conducting. This process will be repeated as long as contact 9^a remains closed. During the interval in which current 65 is supplied to winding 6, the magnetic core 4 of the reactor A is saturated, so that the reactance of winding 5 is relatively low, with the result that a relatively large amount of current is supplied to the track rails from secondary 2. During the interval in which the neon tube is non-conductive, no current is supplied to winding 6, and so the reactance of 70 winding 5 is relatively high, and the amount of current supplied to the track rails is relatively small. The frequency at which current is supplied to the control winding 6 will, of course, depend on the capacity value of the condenser C^A, and also on the values of 75 resistances 7 and 8^a.

When contact 9^b is closed and contact 9^a is open, the apparatus will function in the same manner as before, except that the frequency of the current supplied to winding 80 6 will be different, because of the different capacity value of the condenser C^B. When contact 9^c is closed, the apparatus will still function as before, except that the frequency 85 of energization of winding 6 will again be 90 100

different because of the different capacity value of the condenser C^c .

Resistances 8^a , 8^b and 8^c are connected in series with the condensers for the purpose of regulating the rate of discharge of these condensers. One purpose of the variable resistance 7 is to adjust the rate of charging of the condensers; this resistance also serves to determine the current value at which the neon tube becomes conducting because the I. R. drop across resistance 7 determines the voltage across the neon tube. These resistances, therefore, taken together with the capacity values of the condensers, may be used to adjust the frequency of periodic variation 10 of the current supplied to the track rails by the transformer secondary 2.

Although as here shown the control winding 6 is used to govern the reactance of winding 5, it is understood that winding 6 may be used in any other suitable manner to periodically vary the amplitude of the current supplied to the rails from secondary 2. For example, winding 6 may be the heating 20 element of a thermo-sensitive relay, the thermo-sensitive element of which is interposed between the secondary 2 and one of the track rails.

Although I have herein shown and described only one form of apparatus embodying my invention, it is understood that various changes and modifications may be made therein within the scope of the appended claims without departing from the 35 spirit and scope of my invention.

Having thus described my invention, what I claim is:

1. In combination with the rails of a railway track and a source of alternating current connected therewith, a reactor having two windings one of which is interposed between said source and a track rail, and means including a neon tube for periodically supplying current to the other winding of said 45 reactor and thereby periodically varying the amplitude of the current supplied to the rails from said source.

2. In combination with the rails of a railway track and a source of alternating current connected therewith, an impedance interposed between said source and a track rail, and means including a neon tube for periodically varying the value of said impedance and thereby periodically varying the 55 amplitude of the current supplied to the rails from said source.

3. In combination with the rails of a railway track and a source of alternating current connected therewith, a circuit including a source of unidirectional current and a winding and a neon tube, a condenser connected across said circuit in multiple with the unidirectional source, whereby said tube 60 periodically becomes conductive to supply current to said winding, and means respons- 65

sive to the periodic supply of current to said winding for periodically varying the amplitude of the current supplied to the rails from said alternating source.

4. In combination with the rails of a railway track and a source of alternating current connected therewith, a reactor having two windings the first of which is interposed between said source and a track rail, a circuit including a source of unidirectional current and the second winding of said reactor and a neon tube, and a condenser connected across said circuit in multiple with the unidirectional source whereby said tube periodically becomes conductive to supply current to said second winding and to thereby periodically vary the amplitude of the current supplied to the rails from said alternating current source. 70 75 80

5. In combination with the rails of a railway track and a source of alternating current connected therewith, a circuit including a source of unidirectional current and a winding and a neon tube, a plurality of condensers having different capacity values, 85 means for selectively connecting said condensers across said circuit in multiple with the source of unidirectional current whereby said tube becomes conductive to supply current to said winding at different frequencies 90 depending upon which condenser is connected with the circuit, and means responsive to the periodic supply of said current to said winding for periodically varying the amplitude of the current supplied to the rails from 95 100 said alternating source.

6. In combination with the rails of a railway track, a transformer having a primary constantly supplied with alternating current, said transformer having a first secondary 105 connected with the rails of said track, a second secondary on said transformer supplying current to the input circuit of a rectifier, a control circuit supplied with unidirectional current by said rectifier and including a 110 winding and neon tube, a condenser connected across said control circuit in multiple with the rectifier whereby said tube periodically becomes conductive to supply current to said winding, and means responsive to the 115 periodic supply of current to said winding for periodically varying the amplitude of the current supplied to the track rails from said first transformer secondary. 120

7. In combination with the rails of a railway track and a source of alternating current connected therewith, a circuit including a source of unidirectional current and a winding and a neon tube, a condenser and a resistance connected in series across said circuit in multiple with the unidirectional source whereby said tube periodically becomes conductive to supply current to said winding, a resistance interposed between said 125 source and said condenser for controlling the 130

charging rate of the condenser, and means responsive to the periodic supply of current to said winding for periodically varying the amplitude of the current supplied to the rails from said alternating current source.

5 8. In combination with the rails of a railway track and a source of alternating current connected therewith, an impedance interposed between said source and one of the
10 track rails, a winding for varying the value of said impedance, and means including a neon tube for periodically supplying current to said winding and thereby periodically varying the amplitude of the current supplied to the rails from said source.

15 9. In combination with the rails of a railway track, a source of alternating current connected therewith, a control winding, a neon tube, a condenser, a charging circuit
20 for said condenser including a source of unidirectional current, a discharge circuit for said condenser including said neon tube and said control winding in series, and means governed by said control winding for periodically varying the amplitude of the current supplied to the rails from said source.

25 In testimony whereof I affix my signature.
